UNITED STATES PATENT OFFICE.

JOHN A. KASZEWSKI, OF CHICAGO, ILLINOIS.

MILK-BOTTLE-LOCKING DEVICE.

1,289,805.

Specification of Letters Patent. Patented Dec. 31, 1918.

Application filed October 16, 1917. Serial No. 196,841.

To all whom it may concern:

Be it known that I, JOHN A. KASZEWSKI, a citizen of Poland, Russia, and a resident of the city of Chicago, county of Cook, and 5 State of Illinois, have invented a certain new and useful Milk-Bottle-Locking Device, of which the following is a specification.

My invention relates to milk bottle locking devices, that is to that class of devices, 10 the purpose of which is to prevent theft of milk bottles after delivery of the same by the milkman and before the rightful owner or recipient of the bottle calls for the same at the place of delivery thereof by the 15 milkman.

The object of my invention is the production of a device of the character mentioned, which may be of durable and economical construction and through the medium of which a milk bottle may be effectually locked.

A further object is the production of a device of the character mentioned which may be readily and easily operated.

25 Other objects will appear hereinafter.

The invention consists in the combinations and arrangements of parts hereinafter described and claimed.

The invention will be best understood by 30 reference to the accompanying drawing forming a part of this specification, and in which,

Figure 1 is a side elevation of the device showing the same in position of use or with 35 a bottle arranged in operative relation therewith,

Fig. 2, a top plan view of the device as seen in Fig. 1, a portion of the guard member of the device being broken away,

40 Fig. 3, an enlarged central vertical section of the device as positioned in Fig. 2,

Fig. 4, a view similar to Fig. 3, with the device shown in inoperative or idle position,

Fig. 5, a top plan view of the bottle gripping jaws,

Fig. 6, a plan view of a shiftable pin included in the construction,

Fig. 7, an end view of a latch employed in the construction,

50 Fig. 8, a rear view of said latch,

Fig. 9, an end elevation of the jaw carrying member, and

Fig. 10, a plan view of Fig. 9.

The preferred form of construction as 55 illustrated in the drawings is designed for

use in connection with a door frame illustrated at 15 and the usual hinged door illustrated at 16. Upon the door frame 15 is arranged a base plate 17 rigidly secured thereto by screws 18. The plate 17 is formed 60 adjacent its upper end with forwardly projecting spaced ears or lugs 19, in which is arranged a pin or bolt 20, which is adapted for pivotal as well as longitudinal shifting movement. An overhanging flange or cap 65 21 connects the upper edges of ears 19 as seen in the several views.

Swingingly mounted upon the pin 20 is a jaw carrier 22 formed of a single piece of sheet metal bent upon itself so as to form 70 two spaced parallel portions, said portions being connected by bands or straps 23, which pivotally embrace the pin 20. Arranged between the spaced portions of member 22 and pivotally connected therewith at 24' are 75 jaws 24 of such shape as to be adapted, when at their inner terminals of movement, to embrace the neck of a conventional milk bottle shown at A, in order to lock the bottle to the device. The jaws 24 are formed 80 with intermeshing teeth 25, as seen in Fig. 5, which result in simultaneous movement of said jaws, as will be readily understood. Shoulders 26 and 26' at the inner ends of 85 said jaws limit outward swinging thereof, and shoulders 27 and 27' are adapted to engage against the inner sides of ears or lugs 19 to limit inward swinging of said jaws. Above said jaws is provided a sort of guard 28 to prevent removal of the milk 90 bottle cap. The member 28 is rigidly secured to the jaw carrier 22.

Coöperating with the jaws 24 is a latch 95 29, the same being formed at its ends with ears 29' as seen in Fig. 8, which pivotally embrace the pin 20, said latch being adapted to fit snugly between the portions 23 of the jaw carrier 22. The forward or free end of the latch 29 is adapted to engage between shoulders 30 on the jaws 24 in order to lock 100 said jaws in operative relation, that is at their inner terminals of movement. Coöperating with said latch is a leaf spring 31 arranged under the cap 21, said leaf spring being adapted to engage with a lug or projection 32 on the latch in order to normally press said latch toward operative position. The ears 29' of said latch project, at their under sides, beyond the portions 23 of the 105 jaw holder 22, said ears being formed with 110

shoulders or points 33 which are adapted to engage against the base plate 17 in order to limit pivotal movement of said latch toward said plate. The arrangement is such that, as the jaw carrier is swung downwardly toward vertical position, the shoulders 33 will engage against the base plate 17 and serve to raise the free end of said latch to a position out of operative relation with the shoulders 30 of the jaws 24, as is clearly seen in Fig. 4. This being the case, when the jaw carrier is in depending vertical position, or idle, the jaws 24 will be released so as to permit outward swinging of the same. Immediately upon said jaw carrier being swung toward raised or horizontal position, which is the operative position thereof, the shoulders 33 will be moved from engagement with the plate 17 to permit of the free end of the latch being rocked, under the influence of spring 31, to a position between the shoulders 30 of the jaws 24, as clearly seen in Fig. 3. This being the case, when the device is swung upwardly, a bottle arranged therein, and the jaws 24 rocked inwardly into engagement with the bottle, the latch 29 will automatically, under the influence of spring 31, move to operative position where the same will lock said jaws in bottle-engaging position.

In order to effect movement of the latch to inoperative position, that is to a position to release the jaws 24, the pin 20 is provided with a cross piece 34, as is clearly seen in Figs. 3, 4 and 6. Said cross piece 34, when the pin 20 is at its left hand or inner terminal of movement, engages with a ledge 35 formed upon the jaw carrier 22, which prevents any rocking movement of said pin. When said pin is pulled out to its right hand or outer terminal of movement, the cross piece 34 will be brought into registration with a notch 36, which will allow for rocking of said cross piece and hence the pin 20. One end of said cross piece is adapted to engage against the under side of latch 29 so that when thus rocked, said cross piece will rock said latch to releasing position. Thus, in order to unlock a bottle once locked in the device, it is necessary to pull the pin 20 to its outer terminal of movement and then oscillate the same in order to move the latch 29 to releasing position. The device is, however, so arranged that when the door 16 is closed the pin 20 will be locked thereby at its inner terminal of movement. This being the case it will be seen that in order to unlock the device to release a bottle therefrom it will first be necessary to open the door in order to permit of shifting of the pin 20 to its outer terminal of movement.

In using the device then it will be seen that when the same is in depending vertical position, or idle, the jaws will be free for movement as desired. Thus, the milkman

in delivering the milk, needs only to rock the jaws outwardly with the device in idle position, then swing the device upwardly, insert the bottle, and press the jaws inwardly into operative relation with the bottle. The bottle will be positively locked against release until the door is opened, in which event, in order to release the bottle it will only be necessary to shift the pin 20, then rotate the same, which, as above pointed out, effects unlocking of the jaws to release the bottle.

While I have illustrated and described the preferred form of construction for carrying my invention into effect, this is capable of variation and modification without departing from the spirit of my invention and I therefore do not wish to be limited to the precise details of construction set forth but desire to avail myself of such variations and modifications as come within the scope of the appended claims.

Having described my invention what I claim as new and desire to secure by Letters Patent is:

1. A milk bottle lock comprising a pair of gripping jaws movable toward and from each other and mounted to swing in unison about a horizontal axis; and means adapted to lock said jaws in operative relation in one position thereof about said horizontal axis, and to release said jaws, to permit of movement thereof to bottle-releasing position, in another position of said jaws about said axis, substantially as described. 90

2. A milk bottle lock comprising a pair of gripping jaws movable toward and from each other and mounted to swing in unison about a horizontal axis; and means adapted to lock said jaws in operative relation, when swung about said horizontal axis to horizontal position, and to release said jaws to permit of movement thereof to bottle-releasing position, when said jaws are swung about said axis to vertical position, substantially 100 as described. 105

3. A milk bottle lock comprising a pair of gripping jaws movable toward and from each other and mounted to swing in unison about a horizontal axis; means adapted to lock said jaws in operative relation, when swung about said horizontal axis to horizontal position, and to release said jaws to permit of movement thereof to bottle-releasing position, when said jaws are swung about said axis to vertical position; and means for fixing the terminals of swinging movement of said jaws at said position thereof, substantially as described. 115 120

4. A milk bottle lock comprising a pair of gripping jaws movable toward and from each other and mounted to swing in unison about a horizontal axis; and a latch adapted to lock said jaws in operative relation, when swung about said horizontal axis to hori- 125 130

zontal position, and release said jaws to permit of movement thereof to bottle-releasing position, when said jaws are swung about said axis to vertical position, substantially as described.

5. A milk bottle lock comprising a pair of gripping jaws movable toward and from each other and mounted to swing in unison about a horizontal axis; a latch adapted to 10 lock said jaws in operative relation, when swung about said horizontal axis to horizontal position, and release said jaws to permit of movement thereof to bottle-releasing position when said jaws are swung about 15 said axis, to vertical position; and manually controlled means for moving said latch to inoperative position, substantially as described.

6. A milk bottle lock comprising a pair of 20 gripping jaws movable toward and from each other and mounted to swing in unison about a horizontal axis; a latch adapted to lock said jaws in operative relation, when swung about said horizontal axis to horizontal 25 position, and release said jaws to permit of movement thereof to bottle-releasing position, when said jaws are swung about said axis, to vertical position; a manually controlled shiftable member for moving said 30 latch to inoperative position; and means for rendering said shiftable member inoperative except when said member is shifted to a certain position, substantially as described.

7. A milk bottle lock comprising a pair of 35 gripping jaws movable toward and from each other and mounted to swing in unison about a horizontal axis; a latch adapted to lock said jaws in operative relation, when swung about said horizontal axis to horizontal 40 position, and release said jaws to permit of movement thereof to bottle-releasing position, when said jaws are swung about said axis to vertical position; a rockingly and shiftably mounted member adapted, when 45 rocked, to move said latch to inoperative position; and means for preventing rocking of said member except when said member is shifted to a certain position, substantially as described.

50 8. A milk bottle lock comprising a pair of

gripping jaws movable toward and from each other and mounted to swing in unison about a horizontal axis; a latch adapted to lock said jaws in operative relation, when swung about said horizontal axis to horizontal 55 position, and release said jaws to permit of movement thereof to bottle-releasing position, when said jaws are swung about said axis to vertical position; a rockingly and shiftably mounted member adapted, when 60 rocked, to move said latch to inoperative position; and a coöperating pin and ledge for preventing rocking of said member, said ledge having a notch cut therein for registration with said pin whereby said member 65 may be operatively rocked only when said member is shifted to bring said pin into registration with said notch, substantially as described.

9. In a milk bottle locking device, the 70 combination with a door, of bottle-engaging means mounted to swing about a horizontal axis; means for locking said bottle engaging means in engaging relation with a bottle, when said bottle engaging means is in horizontal position; and means for unlocking 75 said bottle engaging means to permit of release of the bottle, said locking means being held in inoperative position when the door is closed, substantially as described. 80

10. In a milk bottle locking device, the combination with a door, of a bottle-engaging means mounted to swing about a horizontal axis; means for locking said bottle engaging means in engaging relation with a 85 bottle, when said bottle engaging means is in horizontal position; and a shiftably mounted member for unlocking said bottle engaging means to permit of release of the bottle, said member being held in inoperative 90 position when the door is closed, substantially as described.

In witness whereof I have signed my name to this specification in the presence of two subscribing witnesses.

JOHN A. KASZEWSKI.
